UNITED STATES PATENT OFFICE.

FREDERICK W. LINAKER AND THEODORE M. BRUBACK, OF DU BOIS, PENNSYLVANIA.

SOOT-CLEANER-OPERATING MECHANISM.

Application filed April 25, 1923. Serial No. 334,524.

This invention relates to boiler cleaners of the type having a rotatable or oscillatable tubular part, known as the cleaner element, which projects into the boiler and has nozzles for ejecting jets of steam against or among the boiler tubes. Such cleaner elements project out through the boiler setting and are connected by a stuffing box to a steam supply pipe, a valve being applied either in 10 said pipe or in the connection or head adjacent the stuffing box. For rotating the element, it is common either to apply a wheel on the element between the boiler setting and the stuffing box in a position to be reached, 15 or in case of overhead cleaning elements to apply a sheave operated by a chain from beneath; or for intermittently turning the element to apply to it a ratchet wheel engaged by a pawl on a lever or rocker which is suitably operated either directly or through a 20 rod or chains. A suitable reverse-acting ratchet mechanism for this purpose is shown in our Patent No. 1,590,300, dated June 29, 1926.

It is desirable to control the admission of steam to the element by a valve located in proximity to the entrance to the element, preferably in a connection or head to which the element is connected through the stuffing box. In such construction as the valve and element are closely adjacent, it is often preferable to provide the same operating mechanism for turning the element and for opening or closing the valve. An example of such construction is set forth in the patent to 30 Frederick W. Linaker, No. 1,413,601, dated April 25, 1922. In that patent a single operating mechanism may be connected at one time to turn the element and at another time 35 to operate the valve, or in another construction the operating mechanism is connected always to the element and is coupled to the valve at suitable times for opening and closing the valve.

The present invention provides an improved mechanism for turning the element intermittently, and which is adapted at the beginning of the operation to open the valve for admitting steam to the element and upon the return movement at the end of the operation to close the valve and shut off the steam, the valve operations being performed automatically.

To these ends the present invention provides a novel mechanism, the nature and operation of which will be developed as the de-

scription proceeds. Its preferred embodiment is illustrated in the accompanying drawings, wherein,—

Figure 1 is a plan view, partly in horizontal section.

Fig. 2 is an end elevation, partly in section on the line 2—2 in Fig. 1.

Fig. 3 is an elevation, looking in the opposite direction from Fig. 2, showing the 65 clutch, the view being partly in section on the line 3—3 in Fig. 1.

Fig. 4 is a rear elevation, showing the ratchet mechanism, the element being in section, on the line 4—4 in Fig. 1.

Fig. 5 is a fragmentary side elevation of the parts shown in Fig. 4, looking from the left in that figure.

Fig. 6 is a side elevation, looking from the right in Fig. 4, or from the bottom and upwards in Fig. 1, the boiler setting being in vertical section.

Referring to the drawings, A may be any usual boiler setting or furnace wall, B the usual bushing therein having the usual cap C, within which is mounted to turn any usual form of oscillatable or rotatable cleaner element D. The portion of this element projecting into the boiler is not shown, its construction being well understood; it is sufficient to say that it projects between or among the boiler tubes, and has along usually one side a series or row of nozzles for ejecting jets of steam to impinge against the boiler tubes and clean them of soot. As the 80 tube is turned, these jets swing angularly and impinge on the successive surfaces, or surfaces of successive tubes, so as to clean the soot from the tubes over whatever radius is practicable. Usually the element turns from a 85 fixed or variable starting point or position of rest through a given arc which varies with different boilers or types of boilers, and then turns back to the same starting point, or to 90 some other position of rest.

The cleaner element D passes through a stuffing box E into a connecting piece or head F which receives steam through an inlet pipe G. The steam controlling valve is best applied within the head F. The valve most suitable to the present invention is one of the sliding disk type, the sliding disk being carried on an arm, and the head F made large enough to accommodate the swinging movements of the valve and arm between the open and closed positions. In Fig. 2 the valve is lettered H and the valve seat or opening is let-

tered I, the valve arm being lettered J and fixed on an oscillatory stud K, which passes out through the cap of the head and has fastened on its outer end a sector L, which has 5 two rows of sector teeth a a'. The arm J has a stop shoulder J'.

A rotary driving shaft M is arranged to be driven by the operator in any suitable manner, as by being provided with a sprocket 10 wheel or sheave N to be turned by a chain from beneath. On the hub of this wheel or on the shaft is fixed a pinion b which meshes with the sector teeth a. Another pinion b', normally loose on the shaft, meshes with the 15 sector teeth a'. This pinion is clutched to the shaft at certain times as will be explained later.

The shaft M extends preferably parallel with the element D and at its rear end has 20 a crank M' which connects through a pitman or connecting rod P with a rocker frame or lever Q which carries a double-acting pawl Q' engaging the teeth of a ratchet wheel R which is fastened on the element D, so that 25 as the crank turns, it rocks the frame Q, and the pawl intermittently engaging the ratchet teeth pushes them in one direction or the other, and consequently rotates the ratchet R and element D intermittently in a corresponding 30 direction.

It is needless to describe the details of the ratchet mechanism, as the one illustrated is of essentially the construction shown in our said Patent No. 1,590,300, excepting only 35 that it has not the stops, lettered m n l l in that patent, for limiting the oscillations of the ratchet rocker frame, these being unnecessary in the present construction because such limitation is afforded by the throw of 40 the crank M'. Such ratchet mechanism has means for reversing the pawl Q' when the element has been turned to each extreme of its movement and it is desired to ratchet it back toward its starting point, this means 45 being operated through stop pins c, each of which may be set in one or another of suitable spaced holes or sockets d in the wheel R, to determine the point at which the reversing movement shall occur. The stop pin acts to 50 displace a rocker R' having pinion-teeth meshing with teeth on the pawl Q'. All these parts are fully illustrated and described in our said Patent No. 1,590,300.

The shaft M carries a clutch S, the purpose 55 of which is to couple the pinion b' to the shaft when necessary, and to release it therefrom at other times. In the construction shown the clutch S comprises a clutch cup e formed on one end of a sleeve f, the other end 60 of which is fastened to the pinion b', preferably by forming them integral. Within the cup e is a disk g, keyed on the shaft M. On this disk g is carried a pin h to which are pivoted two clutch arms i and j. The 65 arm i, which may be called a tooth arm, is

formed with a tooth i' which is adapted to engage with a tooth k projecting on the inner face of the cup e. The other arm j carries a roller l which is adapted to be acted on by a coned or tapered end of a rider m to force 70 it outward against the pull of a spring n, drawing it toward the axis. The arm j has a tail or stop arm j' which may move between two stop projections o o' on the disk g. The tooth arm i is prolonged at p and its inturned 75 end forms a stop shoulder which abuts against a stop projection q on the inner arm j, the two arms being pressed apart by a spring r. When the coned end of the rider m is withdrawn, the spring n draws the roller 80 l toward the axis, and the tooth i' clears the tooth k; when the cone pushes out the roller l, the arm i is also thrown out by its spring r and its tooth engages the tooth k, so that the shaft M and sleeve f are locked together, 85 when turning on one direction, but owing to the ratchet shape of the teeth i' k, they may pass each other when revolving in the contrary direction.

The rider m is caused to travel along the 90 shaft M by the latter being formed with screw-threads and the rider made as a nut. The rider has a lateral arm terminating in a roller m', which roller travels in a slot s in the bracket F' projecting from the head 95 F which supports the shaft M and its appurtenances. Thus as the shaft revolves, the rider m is propelled in one direction or the other until stopped either at its right-hand end through the operation of the clutch and 100 appurtenant parts, or at its left-hand end by striking a stop nut T which may be screwed along the threaded shaft and fastened thereon in any set position by a set screw. The adjustment of the nut T affords in effect a 105 revolution counting device and is for the purpose of variably limiting the number of revolutions which the shaft M may make in one direction.

The operation will now be explained. In 110 the position of rest, the valve is closed, steam being shut off from the cleaner element, and the first thing to be accomplished by the operation is the opening of the valve to admit steam for cleaning. To this end the operator turns the shaft M in the appropriate direction by pulling the chain hanging from the sheave N. At this time both pinions b b' are fast on the shaft M, and as the rotation is 115 in the direction of the arrow x in Fig. 2, the first effect is to move the sector L upward, and thereby start the valve H upward to uncover the seat I and admit steam. To fully open the valve may require several turns of the shaft; as the shaft turns, its crank M' 120 imparts reciprocating movements through the pitman P to the rocker Q of the ratchet, and at each movement its pawl pushes the ratchet wheel R around the distance of one tooth (preferably about fifteen degrees), 125 130

leaving it at rest during the return stroke; as the shaft M is turned, the rider m travels toward the left in Fig. 1, and as soon as its coned end passes the roller l, the lever j is drawn inward by its spring, thereby withdrawing the tooth i' from the tooth k of the clutch cup, and unclutching the pinion b' from the shaft. From the instant of such unclutching the sector L is operated solely by the pinion b acting on its teeth a, and this continues until the lowermost tooth of the teeth a is pushed above the pinion b to the position shown in Fig. 2, after which the pinion may revolve freely without affecting the sector, so that the valve remains stationary in its open position. When the rider m reaches the end of its travel and strikes the stop nut T, it blocks the further rotation of the shaft and the operator then pulls the chain on the opposite side, and thereby turns the shaft in the opposite direction. When the pin c on the wheel R strikes the rocker R', the pawl Q' is thrown over and consequently the further rotation of the shaft M (in either direction) ratchets the element D back towards its starting point. When the coned end of the rider again acts on the roller l the tooth i' is pushed out into the path of the tooth k which it strikes in the course of the next revolution, and thereupon carries the cup e with it, so that the pinion b' is again clutched to the shaft N. This clutching accomplishes the starting backward of the valve, this being done by the pinion b' being in mesh with the prolonged portion of the sector teeth a', so that the sector is turned until its teeth a are engaged by the pinion b, after which the sector is turned by both pinions (or it might be turned by either) until the valve is fully closed. This completes the operation, although the operation may be repeated if necessary to more fully accomplish the soot cleaning operation.

The purpose of the bevelling of the teeth i' k on one side and the provision of the two arms j i and their spring r is, first, to prevent breakage in case the tooth i' were to move out against the body of the tooth k, this being accompanied by a yielding of the toothed arm i against its spring r; second, to permit the shaft M to turn in the direction for opening the valve without necessarily entraining the pinion b', since in this movement the parts turn in the direction of the arrow y in Fig. 3, so that the tooth i' simply wipes past the tooth k and snaps by it.

While it is sufficient to have one tooth k and i' so related that when they engage, the pinion teeth b' coincide with the teeth of pinion b; yet it is within the invention to provide a greater number of clutch teeth if desired so long as the same result is accomplished.

The pitch of the thread on the shaft M is suitably proportioned to the number of teeth in the ratchet wheel R, and to the number of

positions to which the reverse pins c can be adjusted in the holes d. It results that the stop nut T may be adjusted to any suitable position corresponding to the varying arc through which the element D is turned. The adjustment of the nut T and of the stop screws c is made by the erector in setting up the apparatus in order to turn the element the proper number of degrees according to the requirements of the particular boiler in question. When the stop T is set fully to the left in Fig. 1, the apparatus will turn the element D through an entire revolution; and a lesser arc may be determined by the adjustment of the stop nut T and the corresponding adjustments of the pawl reverser.

The mechanism may be greatly varied within the scope of the invention, as set forth in the subjoined claims. It will be understood that the part m, herein called a "rider," is essentially a travelling part which is propelled in one direction or the reverse according to the direction in which the operating or driving shaft M is being turned, and is not limited to a part which is propelled by a screw-thread, or to one moving in a straight line; its essential function is to operate a clutch or connecting part which controls the closing of the steam valve as the element approaches to or reaches its final position of rest, and determines the opening movement of the valve during or preceding the contrary movement imparted to the element.

The mode of operation of the mechanism may be varied according to the relative setting of the stop nut T and the pawl reversing pins c c. If the construction of the boiler is such that it is desirable for the element to always stop in one certain angular position, or position of rest, so that at each operation it will start from that position, swing through a given arc and return to the same position, then the stop pins will be set to trip or reverse the pawl at the end of the swinging movement, and again upon the return to the initial position; and the stop nut T will be set to stop the rotation of the driving shaft coincidently with the tripping of the pawl at the end of the active movement. In other cases, however, where it is admissible for the position of rest of the cleaning element to vary after each operation, then the relative setting of the stop pins and nut will be different; in such case, for example, the nut may first stop the rotation of the driving shaft before the element has reached the end of its rotative travel, so that after the operator reverses the rotation of the driving shaft, and during its backward movement, the ratchet action will continue to turn the element in the same direction as before, until the stop pin trips the pawl, whereupon the element will be rotated in the reverse direction or back toward its starting point, in which case it will travel through a lesser number of degrees before it

is stopped by the stopping of the driving shaft, due to the rider *m* reaching the end of its movement. Thus adjusted, the nozzles of the element will point in a different angular direction each time the operation is completed, so that after each operation the element is brought to a new stopping point. Thus, by varied settings of these respective members, the operation of the mechanism may be varied 10 to a considerable extent in order to better adapt it to a variety of boiler constructions.

What we claim is:—

1. A mechanism for rotating a rotatable boiler soot cleaner element and for controlling admission of steam thereto, comprising a rotary driving member adapted to be rotated first in one direction for a number of revolutions and then in the other direction for a number of revolutions, means operated therefrom for turning the element from an initial starting position to a final stopping position, a valve, and automatic means for connecting the valve to said driving member to close the valve as the cleaner element is moved to its 25 final stopping position and to open the valve as the element is next moved from said position.
2. A mechanism for rotating a rotatable boiler soot cleaner element and for controlling admission of steam thereto, comprising a rotary driving member adapted to be rotated first in one direction for a number of revolutions and then in the other direction for a number of revolutions, a ratchet mechanism 30 operated therefrom for turning the element from an initial starting position to a final stopping position, a valve, and automatic means for connecting the valve to the driving member to close the valve as the element 35 approaches to and to open the valve as the element recedes from said final stopping position.
3. A mechanism for intermittently rotating a rotatable boiler soot cleaner element and for controlling admission of steam thereto, comprising a rotary driving member adapted to be rotated first in one direction for a number of revolutions and then in the other direction for a number of revolutions, means 40 operated therefrom for turning the element by a step by step movement first from a position of rest and then back toward said position, a valve, and automatic means for operating said valve from said driving member at 45 the beginning and end of the movement so imparted to the element, whereby to shut off steam from the element in its position of rest and admit steam as the element is turned from such position.
4. A mechanism for rotating a rotatable boiler soot cleaner element and for controlling admission of steam thereto, comprising a rotary driving member, means operated therefrom for turning the element, a reciprocatory rider propelled by said driving

member, means for adjusting the travel of the rider, a valve, and valve operating mechanism driven from said driving member under control of said rider.

5. A mechanism for rotating a rotatable boiler soot cleaner element and for controlling admission of steam thereto, comprising a rotary driving member, means operated therefrom for turning the element, a rider propelled by said driving member, an adjustable stop for coacting with the rider to vary its travel, whereby the adjustment of said stop varies the extent of rotation of the driving member, a valve, and valve operating mechanism driven from said driving member under control of said rider.

6. A mechanism for intermittently rotating a rotatable boiler soot cleaner element and for controlling admission of steam thereto, comprising a rotary driving member, a ratchet mechanism reciprocated therefrom for turning the element, said mechanism being automatically reversible to rotate the element in first one direction and then the other, a valve, and means for connecting the valve to the driving member as said member approaches a definite position of rest and disconnecting it as said member recedes from such position.

7. A mechanism for rotating a rotatable boiler soot cleaner element, and for controlling admission of steam thereto, comprising a rotary driving member, means operated therefrom for turning the element, a rider propelled by said driving member, a clutch operated by said rider, a valve, and valve operating mechanism controlled by said clutch.

8. A mechanism for rotating a rotatable boiler soot cleaner element, and for controlling admission of steam thereto, comprising a rotary driving member, means operated therefrom for turning the element, a rider propelled by said driving member, an adjustable stop for varying the travel of said rider, a clutch operated by said rider, a valve, and valve operating mechanism controlled by said clutch.

9. The combination of claim 7, the clutch comprising mutually engaging parts, and the rider having a cam portion for determining the engagement of said parts.

10. The combination of claim 7, the clutch comprising a member turning with the driving member and a member connected to the valve operating mechanism, and means for connecting said clutch members, comprising a spring-pressed part movable by said rider for engaging said members.

11. The combination of claim 7, the clutch comprising a member connected to the driving member, a cup-shaped member connected to the valve operating mechanism and having an internal tooth, and means for connecting said members, comprising a spring-pressed arm carried by the former having a tooth for 130

- engaging said tooth, and the rider having a cam portion for engaging said spring-pressed arm for moving it to engage said teeth.
- 5 12. The combination of claim 7, the clutch comprising a member connected to the driving member, a cup-shaped member connected to the valve operating mechanism and having an internal tooth, and means for connecting 10 said members, comprising two spring-pressed arms carried by the former normally movable together, the one having a tooth for engagement with said tooth, and the other adapted for engagement by said rider to move said 15 arms to engage said teeth, and said tooth-carrying arm having a stop engagement with said other arm, with a spring for pressing them into such engagement, whereby said tooth-carrying arm may yield to a backward movement and permit said teeth to pass each other.
13. A mechanism for rotating a rotatable boiler soot cleaner element and for controlling admission of steam thereto, comprising a rotary driving member, means operated 25 therefrom for turning the element, a valve, a valve-operating mechanism therefor, adapted to open and close the same, comprising a toothed rack connected to the valve, a pinion on said driving member for engagement with 30 said rack, adapted after the opening movement of the valve to carry said rack beyond engagement with the pinion, so that further movement of the driving member to operate the element will not move the valve, and 35 means operable before the closing movement of the valve for starting the backward movement of said rack to bring its teeth into engagement with said pinion, whereby to effect the closing of the valve.
- 40 14. A mechanism for rotating a rotatable boiler soot cleaner element and for controlling admission of steam thereto, comprising a rotary driving member, means operated therefrom for turning the element, a valve, a 45 valve-operating mechanism therefor adapted to open and close the same, comprising two racks connected with the valve, and two pinions connected with the driving member, the one rack travelling beyond its driving pinion and the other rack remaining in mesh with 50 its pinion, and means for respectively connecting or disconnecting the latter pinion to and from the driving member.
- 55 15. A mechanism for rotating a boiler soot cleaner element and for controlling admission of steam thereto, comprising a rotary driving member adapted to be rotated in one direction for a predetermined number of revolutions and then in the reverse direction for the 60 same number of revolutions, means operated therefrom for turning the element from an initial starting position of rest to a final stopping position, a valve, gearing for operating said valve normally connected with the driving member and adapted to disconnect there-

from after the valve is opened, and means for re-connecting said gearing to the driving member to close the valve as the element approaches said final stopping position.

16. A boiler soot cleaner having a cleaner element and having a connection for a source of cleaning fluid, and means for intermittently oscillating said element through a predetermined angle of rotation, comprising a rotary driving member adapted to be turned 75 in either direction, an automatic reversing ratchet mechanism operated therefrom for intermittently turning the element first in one direction and then in the other over said angle of rotation, said ratchet mechanism being adapted to effect the regular to and fro traversing of said element through said angle regardless of the direction of rotation of said rotary driving member, in combination with valve mechanism for controlling the 80 supply of fluid to said cleaner, said valve mechanism being operatively connected with said driving member.

17. A boiler soot cleaner according to claim 16, further characterized in that the 90 said ratchet mechanism is actuated by a reciprocating connecting rod eccentrically pivoted to said rotary driving member.

18. A boiler soot cleaner according to claim 16, further characterized in that said 95 rotary driving member is provided with stop means adapted to check its rotation in either direction after a predetermined number of revolutions whereby the number of oscillations of said cleaner element is controlled. 100

19. In a boiler soot cleaner the combination with a rotary cleaner element of driving mechanism comprising a rotating driving member and intervening speed reducing mechanism communicating movement from 105 the driving member to the cleaner element, and adjustable stop means determining the number of revolutions of said driving member adapted to stop the rotation of said driving member after a predetermined number 110 of revolutions, said stop means being independent of the speed reducing means.

20. A mechanism for rotating a rotatable boiler soot cleaner element and for controlling a valve admitting steam thereto, comprising a rotary driving member adapted to be rotated in a series of revolutions, means operated therefrom for turning the element first in one direction and then the other regardless of the direction of rotation of said 120 rotary driving member, a valve actuating device, and automatic means adapted to operatively connect said valve actuating device to said driving member as said member approaches a predetermined point in a certain revolution of the said series and to operatively disconnect said member and actuating device upon a recession of said member from said point in the series.

21. A boiler soot cleaner comprising a 130

boiler cleaner element adapted for connection to a source of cleaning fluid, a driving member for said cleaning element adapted to be rotated for a period in one direction, and 5 for a period in the reverse direction, means for compelling such change in direction, and intermediate mechanism between said driving member and said cleaner element imparting to said cleaner element a series of step 10 by step movements while the driving member is rotated in one direction.

22. A mechanism for operating a boiler cleaner element comprising an operating means for giving such element a step-by-step 15 rotation, a fluid valve, and means for opening and closing said valve operated by said operating means.

23. A mechanism for operating a boiler cleaner element comprising an operating 20 means for giving such element a step-by-step rotation, and a reversing means for said element actuated by said operating means, whereby the cleaner element turns through a predetermined arc in one direction, and 25 then in the reverse direction, a fluid valve, and means for opening and closing said valve operated by said operating means.

24. A mechanism for operating a boiler cleaner element comprising an operating 30 means for giving such element a step-by-step rotation, a reversing means for said element actuated by said operating means, whereby the cleaner element turns through a predetermined arc in one direction, and then in 35 the reverse direction, adjustable means for varying the degree of said arc, a fluid valve, and means for opening and closing said valve operated by said operating means.

25. A mechanism for operating a boiler 40 cleaner element comprising a means for rotating the element from a starting position, a fluid valve, means for opening and closing

said valve, and means for adjusting the degree of angular movement of said element from its starting position whereby the element may travel different degrees of such angular movement during the open period of such valve, and a common means for actuating said element-rotating and valve-operating means.

26. A mechanism for operating a boiler cleaner element, comprising means for giving the element an intermittent or step by step movement, a fluid valve, and means for opening and closing it, said last-named means being non-intermittent and acting to rapidly open or close the valve, and a single device for operating both said means.

27. A boiler cleaner element, a valve for supplying fluid thereto, means for giving the cleaner element a slow step by step turning movement, and means for giving the valve a relatively rapid opening and closing movement, said means being connected to operate together.

28. A boiler cleaner element, a valve for supplying fluid thereto, means for giving the cleaner element a slow step by step turning movement, and means for giving the valve a relatively rapid opening and closing 70 movement, said last-named means maintaining the valve open for a series of step by step movements of the cleaner, whereby in operation the valve may be quickly opened and fluid supplied to the cleaner and the cleaner 75 intermittently turned to a predetermined extent and the valve then quickly closed, and a common means for operating said first two means.

In witness whereof, we have hereunto 80 signed our names.

FREDERICK W. LINAKER.
THEODORE M. BRUBACK.
